[57] CLAIM

The ornamental design for a wooden hockey stick having an elastomeric sleeve about its handle, as shown and described.

DESCRIPTION

FIG. 1 is a front elevational view of a wooden hockey stick having an elastomeric sleeve about its handle showing my new design.

FIG. 2 is a top view thereof.

FIG. 3 is a left elevational view thereof, the right side being a mirror image thereof.

FIG. 4 is a bottom view thereof.

FIG. 5 is a rear elevational view thereof; and,

FIG. 6 is a perspective view thereof.
